US00D768919S

(12) **United States Design Patent** (10) **Patent No.:** **US D768,919 S**
(45) **Date of Patent:** **** Oct. 11, 2016**

(54) **MOUTHPIECE FOR ELECTRONIC VAPING DEVICE**

(71) Applicant: **Altria Client Services LLC**,
Richmond, VA (US)

(72) Inventors: **Eric Hawes**, Midlothian, VA (US);
Traci Martin, Richmond, VA (US);
Melissa Burroughs, Richmond, VA (US);
Berina Yerkic-Husejnovic,
Richmond, VA (US); **Raymond Lau**,
Richmond, VA (US); **Christopher S. Tucker**, Midlothian, VA (US); **Anthony Dibitonto**, Richmond, VA (US); **Marc Suriol**, Richmond, VA (US); **George Stafford**, Richmond, VA (US); **Jamie Nicholson**, Richmond, VA (US); **Mark Breneman**, Richmond, VA (US);
Alistair Bramley, Richmond, VA (US)

(73) Assignee: **Altria Client Services LLC**,
Richmond, VA (US)

(**) Term: **15 Years**

(21) Appl. No.: **29/527,149**

(22) Filed: **May 15, 2015**

(51) LOC (10) Cl. **27-02**
(52) U.S. Cl.
USPC **D27/170**

(58) **Field of Classification Search**

CLAIM

The ornamental design for a mouthpiece for electronic vaping device, as shown and described.

DESCRIPTION

FIG. 1 is a perspective view of the mouthpiece for electronic vaping device;

FIG. 2 is a top view of the mouthpiece for electronic vaping device;

FIG. 3 is a bottom view of the mouthpiece for electronic vaping device;

FIG. 4 is a first side view of the mouthpiece for electronic vaping device;

FIG. 5 is an opposite side view of the first side view of the mouthpiece for electronic vaping device;

FIG. 6 is a front view of the mouthpiece for electronic vaping device; and,

FIG. 7 is a rear view of the mouthpiece for electronic vaping device.

The broken line showing of portions of the mouthpiece depicts environment and forms no part of the claim.
